UNITED STATES PATENT OFFICE.

HARRY ZIMMERMAN, OF FREMONT, OHIO.

SHUTTER-BOWER.

No. 921,785.

Specification of Letters Patent. Patented May 18, 1909.

Application filed November 6, 1907. Serial No. 401,024.

To all whom it may concern:

Be it known that I, HARRY ZIMMERMAN, a citizen of the United States, residing at Fremont, in the county of Sandusky and State of Ohio, have invented certain new and useful Improvements in Shutter-Bowers, of which the following is a specification.

My invention relates to shutter bowers, and more especially to the sill plate and locking devices, and consists in constructing these parts as fully described hereinafter and illustrated in the accompanying drawing, in which,

Figure 1 is a perspective view of a sill plate embodying my invention; Fig. 2 is a cross section on the line 2—2 Fig. 1; Figs. 3, 4, 5 and 8 are perspective views showing the sill plates of different forms; Fig. 6 is a plan in part section showing a sill plate and locking devices arranged on a sill and shutter; and Fig. 7 is a vertical section of the locking bracket.

An embodiment of my invention in a simple form is illustrated in Fig. 5 where, as in the other figures, the sill plate A is made from a single piece of sheet metal with an elevated bridge having at the top a series of bowing holes or sockets 3, a locking hole 5 at one side of the line of bowing holes, and a lateral extension 7 with an incline 10.

In the construction of Fig. 5 the plate is punched to make the sockets and is slit so that it may be bent to form the side flanges 8, 8, and the incline 10, and as this can be done with a punch and flanging machine, and dies are not required, the construction is a cheap one. Preferably, however, the sheet of metal from which the sill plate is to be made is stamped up to form the bridge, extension, and side flanges to the bridge, and also connected side flanges 12 to the extension all in one continuous piece, whereby the flanges of the extension not only impart rigidity thereto, but by their connection to those of the bridge, brace and support the latter. Such strength and rigidity is thus secured that much lighter material than otherwise needed may be used, and the cost of manufacture reduced. Some of the features of my invention hereinafter referred to may however be secured if the article of the shape described is made of cast metal. Any suitable means may be employed to connect the sill plate to the sill. In some cases the screws α may be inserted in the terminal

openings of the bowing opening series as in Fig. 5, but I prefer to extend the plate to form a base portion 15 which may be in the form of wings as in Figs. 1, 3 and 6, or ears as in Figs. 4 and 8, such portions having perforations 16 for the reception of the securing screws.

The sill plate in place on the sill Y as shown in Fig. 6 is used in connection with a brace rod D pivoted to a bracket B attached to the shutter X and having a bent end which may engage the sockets 3 or 5, and a locking bracket E secured to the shutter is provided with a tongue 19 having an opening w through which the hook of the brace rod may pass into the locking socket 5, or one of the bowing sockets which then constitutes a locking socket, the shutter being retained close against the sill. Sometimes, owing to the presence of ice or snow on the sill or the warping of the shutter, the latter cannot be fully closed, but the additional locking socket 5 permits the shutter to be locked in its slightly open position. Inasmuch however as the slight opening of the shutter shifts the longitudinal position of the brace rod, the socket 5 is elongated and the opening w in the tongue 19 elongated to permit the locking effect to be secured.

While the extension 7 may be at one side the center or adjacent to one end of the sill plate, as in Figs. 4 and 8, I prefer to arrange it in the center as shown in Figs. 1, 3, 5 and 6, and it will be seen that the center bowing socket with two on either side constitute a series of three which gives all needed bowing adjustments of the shutter, the two terminal sockets at one end being utilized when the sill plate is used with one shutter, and those at the other end being utilized when the sill plate is used with the other shutter. To secure the shutter in its position against the wall I use a separate sill plate I stamped up of a single plate with perforated ears to receive the retaining screws.

To avoid the necessity of supplying a separate holder to support the brace rod adjacent to the shutter when the rod is not in active use, and to prevent its displacement I so form the tongue 19 as to secure a shelf 20 adjacent to the opening w , the hook of the brace rod resting on this shelf and being prevented from being displaced by a surrounding rib or shoulder v . This I do not here claim as it forms the subject of a separate

application Serial No. 422,025. Neither do I here claim a sill plate with a series of bowing sockets and a locking socket adjacent thereto, nor one made of a single sheet of metal, nor any of the features shown herein and also shown and claimed in my separate applications for Letters Patent Nos. 347,531, 400,653, 400,654 and 400,865.

Without limiting myself to the construction and arrangement shown, I claim:

10. 1. A sill plate consisting of a single sheet of malleable metal formed into an elevated bridge with sockets and side flanges, and a lateral extension with a socket and an inclined face, as set forth.
15. 2. A sill plate consisting of a single sheet of metal bent up to form a bridge, and a lateral extension with an inclined face, the bridge and extension having dependent flanges connected with each other.
20. 3. A sill plate consisting of a single sheet

of malleable metal formed into an elevated bridge with sockets and side flanges, and a lateral extension with an inclined face and a base portion between the extension and bridge portions and with perforations for screws, as set forth.

4. A sill plate having an elevated bridge portion and an inclined extension at one side, and a series of bowing sockets in line with each other at the top of the bridge portion and an elongated locking socket in the top of the extension at one side of one of those on the bridge and between the latter and the incline of the extension.

35 In testimony whereof I affix my signature in presence of two witnesses.

HARRY ZIMMERMAN.
